United States Patent Office.

JOHN A. WROE, OF HAGERSTOWN, MARYLAND.

Letters Patent No. 82,056, dated September 8, 1868.

IMPROVED EXERCISING-CHAIR.

The Schedule referred to in these Letters Patent and making part of the same.

TO ALL WHOM IT MAY CONCERN:

Be it known that I, JOHN A. WROE, of Hagerstown, county of Washington, and State of Maryland, have invented certain new and useful Improvements in Vibratory and Exercising-Chairs for persons leading sedentary lives, invalids, &c.; and I do hereby declare that the following is a full, clear, and exact description of the same, reference being had to the accompanying drawings, and the letters of reference marked thereon, making part of this specification, in which—

Figure 1 is a side elevation.

Figure 2 is a front elevation.

Figure 3 is a vertical section.

Figure 4 is a rear view of the back.

The nature of my invention consists in the construction of chairs for invalids, so that the back, seat, arms, and foot-board shall be hollow, vibratory in principle, and made of any suitable material, or in any convenient form, the chair proper to rest upon pivots or rockers, so as to move to and fro, and made to vibrate by means of spiral springs, disks, or their equivalents, and so arranged in the chair that when acted on by spring-lever, pendulum, or battery, the chair is made to vibrate. To the arms and foot-board are fixed helices, dependent upon or independent of each other. Into the helices the arms and legs are to be inserted. The helices are to be connected with a galvanic battery, and operated on all together or separately, as the case may require.

When the chair is vibrated by the jar of spiral springs, disks, &c., the galvanic battery being in connection with one or more of the helices, the magnetic current is communicated to the part or several parts of the patient in a state of vibration, who may occupy the chair in a sitting posture, the arms and legs being inserted in the helices and the back resting against the vibratory board. A patient seated on this chair in a state of vibration, and under the influence of any remedial agent, will find that it will greatly facilitate the action of such agent in the removal of disease. The patient will also receive the greatest amount of benefit from the magnetic current assisted by the vibratory motion.

To enable others skilled in the art to make and use my invention, I will now proceed to describe its construction and operation.

In the drawings, A is the arm-chair, of usual form; B, the pivot, on which the upper moves upon the bottom part C; D D, the helices for the arms; E E, the helices for the legs. F is a disk, having connected with it a main-spring, f, with a hammer, f¹, which strikes against it. G is a rod, having its upper end looped, which loop slides upon a screw in the centre of the disk. The lower end of the rod G rests on a ledge, g, in the lower part of the chair. H is a spring, which rests upon the rod G and keeps it down. h is a spring-pawl, which works into a single ratchet, h¹, which is under the spring f², which operates upon the hammer f¹.

When the upper chair is moved backward, it is supported by small springs, K, at the corners, and when the chair is down a sufficient distance, the rod G has been forced upward, so that the pawl h carries up the ratchet h¹ until it passes the point of the-pawl, and by the spring h² is made to recoil, and the hammer f¹ strikes the main-spring and thus causes a sudden jar, which affects the back-board, against which the head of the patient is reclining, and this takes place as often as the chair is rocked backward, and as soon as the chair goes forward the spring H forces the rod down to its place on the ledge g.

These spring-striking clocks can be put in the sides, foot-boards, and bottom, and operated upon in a similar manner; and I do not confine myself to the back of a chair in this invention.

Having thus described my invention, what I claim therein as new, and desire to secure by Letters Patent, is—

A vibratory and exercising-chair, when the same is constructed with hollow back, seat, arms, and foot-board, and is so supported upon pivots or rockers that the chair can be readily operated by means of springs, or their equivalents, substantially as described, as and for the purpose specified.

In testimony whereof, I have signed my name to this specification in the presence of two subscribing witnesses.

JOHN A. WROE.
